SPEAKER CABINET

Haruo Ishikawa, 314, 12-35, 1-chome, Matsunoki,
Suginami-ku, Tokyo, Japan

Filed Nov. 6, 1970, Ser. No. 25,863

Claims priority, application Japan June 12, 1970

Term of patent 14 years

Int. Cl. D14—01

U.S. Cl. D26—14

FIG. 1

FIG. 5

FIG. 2

FIG. 4

FIG. 3

FIG. 1 is a front elevation view of the speaker cabinet showing my new design.

FIG. 2 is a side view thereof.

FIG. 3 is a top plan view thereof.

FIG. 4 is a rear view thereof.

FIG. 5 is a top-front perspective view thereof.

The bottom view is identical to the top shown in FIG. 3. The side opposite that shown in FIG. 2 is identical to that shown in FIG. 2.

I claim:

The ornamental design of the speaker cabinet, substantially as shown and described.
